UNITED STATES PATENT OFFICE

158,710

DUPLICATING MACHINE

Richard W. Bailey, Pasadena, Calif., assignor to
Milo Harding Company, Los Angeles, Calif., a
partnership

Application October 5, 1949, Serial No. 5,308

Term of patent 14 years

(Cl. D64—11)

To all whom it may concern:

Be it known that I, Richard W. Bailey, a citizen of the United States and a resident of Pasadena, California, have invented a new, original, and ornamental Design for a Duplicating Machine, of which the following is a specification, reference being had to the accompanying drawings, forming part thereof.

Referring to the drawings:

Figure 1 is a perspective view of a duplicating machine, showing my new design;

Figures 2 and 3 are end elevations of the machine as viewed respectively by the arrows 2 and 3 of Figure 1;

Figure 4 is a top plan view of the machine; and, Figure 5 is a rear elevation thereof.

I claim:

The ornamental design for a duplicating machine, as shown.

RICHARD W. BAILEY.
